DRIVE-IN RESTAURANT OR THE LIKE

Bernard W. Bowman, 2928 S. MacArthur,
Springfield, Ill.

Filed May 23, 1962, Ser. No. 70,250

Term of patent 14 years

(Cl. D13—1)

FIG. 1

The rear of the drive-in restaurant or the like not shown is substantially the same as the front as shown in FIGURE 1.

The dominant features of my design reside in the portions shown in full lines.

I claim:

The ornamental design for a drive-in restaurant or the like substantially as shown and described.
